UNITED STATES PATENT OFFICE.

FLORENCE E. CORY, OF NEW YORK, N. Y., ASSIGNOR TO VANDEVENTER & HORNE, OF SAME PLACE.

DESIGN FOR A CARPET.

SPECIFICATION forming part of Design No. 14,840, dated March 4, 1884.

Application filed January 28, 1884. Term of patent 3½ years.

To all whom it may concern:

Be it known that I, FLORENCE E. CORY, of the city and State of New York, have invented an Improvement in Design for Carpets, of which the following is a specification.

In this design quarternate leaves are arranged in the form shown at *b*, with intermediate sprigs and leaves, *c*, and flowers *d e*, the flowers and leaves being near to each other, so as to cover almost all the surface and produce a highly ornamental and artistic appearance.

I claim—

The design for a carpet, consisting of the quarternate leaves, flowers, and sprigs, arranged substantially as described and represented.

Signed by me this 22d day of January, A. D. 1884.

FLORENCE E. CORY.
